ATTORNEY.

UNITED STATES PATENT OFFICE.

JOHN W. RYAN, OF OVERTON, PENNSYLVANIA, ASSIGNOR OF ONE-HALF TO LOUIE LENNIG ROWLAND, OF OVERTON, PENNSYLVANIA.

CURRENT-INDICATOR.

1,148,481.

Specification of Letters Patent. Patented July 27, 1915.

Application filed December 10, 1914. Serial No. 876,492.

To all whom it may concern:

Be it known that I, JOHN W. RYAN, a citizen of the United States, and a resident of Overbrook, in the county of Philadelphia 5 and State of Pennsylvania, have invented a certain new and useful Current-Indicator, of which the following is a specification.

There are many electrical devices in use which do not show whether the current is on 10 or off; electric irons, cooking utensils and the like are examples of such devices. Electric irons with the current on have been the cause of fires.

The principal object of the present invention is to provide a current indicator for electrical devices which will show whether the current is on or off, and which is simple, comparatively inexpensive and yet thoroughly reliable.

20 The invention will be claimed at the end hereof, but will be first described in connection with the embodiment of it chosen for illustration in the accompanying drawings, in which—

25 Figure 1, is a top or plan view, partly in section, of a device embodying features of the invention. Fig. 2, is a transverse sectional view of the device shown in Fig. 1, and Fig. 3, is a transverse sectional view 30 taken at right angles to the plane of Fig. 2.

35 In the drawings 1, is a suitable case or housing covered as at 2 with glass, so as to provide a transparent opening. Within the housing there is arranged a spool 3 of non-magnetic material and upon this spool is wound a coil 4. Within the spool is arranged a ring 5 of non-magnetic material, which is provided with ears 6.

40 7, is a non-magnetic drum, as of wood, turnable in the ears and shown as mounted on the spindle 8. The drum is provided with a weight as at 9 and with markings of which one "Off" is displayed through the transparent opening when the drum is positioned 45 by its weight 9.

10, are strips of magnetic material applied to the drum for turning it when the coil 4 is energized to show the other marking "On", through the transparent opening.

50 In use the instrument may be mounted upon the electrical device, such as an iron,

cooking vessel or the like, or its working parts may be attached to the iron, cooking vessel or the like, or if preferred the instrument may be arranged in convenient proximity with the iron, cooking device or the like. In any event the coil 4 is included with the electrical device, iron, cooking utensil or the like in the supply circuit. The coil 4 may be a series or current coil, 60 or it may be a shunt or voltage coil. The coil 4 is appropriately wound and its purpose is to create at its center, when it is energized, a magnetic field which operates upon the magnetic strips 10 to turn them 65 together with the drum at right angles to the position in which they appear in Fig. 3. When the current is on or in other words when the electrical device, as an iron, cooking utensil or the like, is in circuit, the coil 70 4 is energized and operates to turn the drum 7 against the influence of its weight into such position that the word "On" is plainly visible and since the word "On" is plainly visible, the user may readily know that the 75 current is on and hence may take proper precautions to prevent accidents. When the current is off, or in other words when the electrical device, iron, cooking utensil or the like is excluded from the circuit, the coil is 80 not energized and the weight 9 turns the drum so as to make the word "Off" plainly visible. The coil 4 is in any event arranged on the same side of the switch as the device 85 in connection with which it is to operate. 85

What I claim is:

1. A current indicator for electrical devices comprising the combination of a housing having a transparent opening, a non-magnetic spool in the housing, a coil on the 90 spool, a non-magnetic ring in the spool having ears, a non-magnetic drum turnable in the ears and provided with a weight and with markings of which one is displayed under the influence of the weight, and magnetic strips applied to the drum for turning it when the coil is energized to show the other marking, substantially as described.

2. A current indicator of the kind recited comprising the combination of a coil, a 100 member of non-magnetic material arranged in the coil and turnable about an axis per-

pendicular to the axis of the coil and provided with two markings, a weight for normally turning the member into the position for showing one marking, and a strip 5 of magnetic material applied to the member and adapted to turn it when the coil is energized to display the other marking.

In testimony whereof I have hereunto signed my name.

JOHN W. RYAN.
